His Attorneys.

Patented July 27, 1926.

UNITED STATES PATENT OFFICE.

FRANK H. LANGMUIR, OF CHICAGO, ILLINOIS, ASSIGNOR TO ST. LOUIS TRUNK HARD-
WARE MFG. CO., OF ST. LOUIS, MISSOURI, A CORPORATION OF MISSOURI.

HAT HOLDER FOR TRUNKS.

Application filed January 23, 1925. Serial No. 4,357.

This invention relates to hat holders for trunks.

An object of the invention is to provide an improved means for supporting a hat holder in 5 different adjusted positions in a trunk in order to accommodate properly hats of different sizes and shapes.

Another object of the invention is to provide means for supporting a hat holder in 10 different adjusted positions with respect to the several walls of the trunk drawer or receptacle in which the hat holder is mounted in order to accommodate hats of varying sizes and shapes. The hat holder is so constructed and designed that a number of hat 15 holders may be mounted on opposite walls of the same trunk drawer or receptacle and adjusted relatively so that a number of hats of the same or of different sizes and shapes 20 may be supported upon respective holders in the same trunk drawer or receptacle.

Other objects will appear from the following description, reference being made to the drawing in which—

25 Fig. 1 is a side elevation of the invention in connection with a supporting wall.

Fig. 2 is a sectional view on the line 2—2 of Fig. 1.

Fig. 3 is an enlarged sectional view on the 30 line 3—3 of Fig. 2.

The device is designed for and capable of attachment to any of the walls of a trunk drawer or receptacle and may be attached in any selected arrangement. As shown, the 35 base 1 of the hat holder has a dished plate 2 attached thereto, the walls of the dished portion of which plate form a polygonal recess of sufficient width and depth to contain a nut 3 and to hold the nut from turning, except when the cushion of the hat 40 holder and the plate 2 are turned.

A bifurcated fixture, the arms of which are integrally united at one end and equally spaced throughout their length, is attached 45 to one of the walls of the trunk drawer or receptacle preferably in an inclined position as shown, although the fixture may be secured in any selected adjustment. Each of the arms of the fixture includes a flat portion 50 4 along its outer edge and around the connection of the arms, and a raised portion 5 along the inner edge, which raised portions engage the head 6 of a screw or bolt 7. A polygonal portion 8 is formed on the screw 55 or bolt and fits within the slot or space be-

tween the arms of the fixture to hold the screw or bolt from turning, but permitting the same to be moved to any desired position in connection with the fixture. The part 8 is about the same thickness as the parts 5 60 of the fixture. The threaded shank of the screw or bolt extends through a hole in the plate 2 and is screwed into the nut 3.

By turning the cushion of the hat holder in one direction the nut 3 is turned to loosen 65 the holder, so that it may be moved to any desired adjustment in connection with the fixture and then the cushion of the holder and the nut may be turned in the opposite direction to clamp the parts and retain the 70 holder in the selected adjustment.

From the foregoing it will be seen that my invention obtains all of its intended objects and purposes in a highly efficient and satisfactory manner and that two or more of 75 the devices may be mounted in the same trunk drawer or receptacle and adjusted relatively to permit a number of hats to be placed in the same drawer or receptacle. The device may be economically manufactured and easily manipulated and adjusted and is strong and durable. I am aware that the construction and relationship of the parts may be varied without departure from the nature and principle of the invention, 80 and I do not restrict myself unessentially in any respect.

What I claim and desire to secure by Letters Patent is—

1. A hat holder comprising a fixture, a clamping element mounted for sliding movements along the fixture, a hat holder, a part in connection with the hat holder having a hole through which said clamping element extends, and an element operative on the side 90 of said part opposite from said fixture to engage said clamping element and cooperate therewith to clamp said part between said elements and rigid with said fixture.

2. A device of the character described 100 comprising a fixture, a clamping element mounted for sliding movements along the fixture, a part to be supported, a member rigid with said part and having a hole through which said clamping element extends, and an element held from rotation relative to said member and operated thereby upon said clamping element to cooperate therewith to clamp said member between 105 said elements and rigid with said fixture.

3. A device of the character described comprising a pair of spaced fixture arms, a clamping element engaging one side of and extending between said arms for sliding movements, a part to be supported, a member in connection with said part having a hole through which said clamping element extends, and an element mounted between said member and said part and operative thereby to engage and cooperate with said clamping element to clamp said member between said elements and rigid with said arms.

4. A hat holder comprising a pair of spaced arms having portions bearing against a support and having portions along their adjacent edges spaced from the support, a screw element having a head between said support and said last named portions of said arms, a polygonal portion in the space between said arms, a hat holder, and a part in connection with the hat holder screwed on the threaded end of said screw element.

5. A device of the character described comprising a fixture, a clamping element having sliding engagement with said fixture, a part to be supported, an additional clamping element arranged to engage said first clamping element, and a member supporting said additional clamping element in connection with said part and preventing said additional clamping element from turning relative to said part.

6. A device of the character described comprising a fixture, a clamping element mounted for sliding movements along the fixture, a part to be supported, a dished member in connection with said part, and an additional clamping member mounted in said dished member and being rotatable thereby to engage said first named clamping element to clamp said dished member in rigid relationship to said clamping elements and said fixture.

FRANK H. LANGMUIR.
